UNITED STATES PATENT OFFICE.

ELEAZAR PARMLY, OF BRIDGEPORT, CONNECTICUT.

DESIGN FOR A SEWING-MACHINE TABLE.

SPECIFICATION forming part of Design No.15,639, dated December 23, 1884.

Application filed May 31, 1884. Term of patent 3½ years.

To all whom it may concern:

Be it known that I, ELEAZAR PARMLY, a citizen of the United States, and a resident of Bridgeport, in the county of Fairfield and State of Connecticut, have invented and produced a new and original Design for Sewing-Machine Tables, of which the following is a specification.

Figure 1 represents a view in perspective of a sewing-machine table representing my design. Fig. 2 represents a perspective view of one of the ornamental faces or moldings.

My design consists of the ornamental faces *a a'*, having the outline of their lower edges scalloped or wavy, thus presenting to the eye the effect of a continuous molding irregular in outline extending across the front edge of the table between the end drawers, *A A'*, as shown at Fig. 1.

I claim—

The design for a sewing-machine table herein shown and described, the same consisting of the ornamental faces *a a'*, the lower edge of said faces being irregular or scalloped in outline, the shape and configuration of each face *a a'* being the same on each side of the center, thus constituting a continuous molding between the end drawers, *A A'*. 20

Signed at Bridgeport, in the county of Fairfield and State of Connecticut, this 24th day 25 30 of May, A. D. 1884.

ELEAZAR PARMLY.
